US00D761738S

(12) **United States Design Patent** (10) **Patent No.:** **US D761,738 S**
Hühne et al. (45) **Date of Patent:** **** Jul. 19, 2016**

(54) **SWITCHING DEVICE FOR PRODUCTION,
DISTRIBUTION OR TRANSFORMATION OF
ELECTRICITY**

(71) Applicant: **Siemens Aktiengesellschaft**, München (DE)

(72) Inventors: **Stephan Hühne**, Fürth (DE); **Tobias Reese**, Bamberg (DE); **Wolfgang Schaller**, Kümmersbruck (DE)

(73) Assignee: **SIEMENS AKTIENGESELLSCHAFT**, München (DE)

(**) Term: **14 Years**

(21) Appl. No.: **29/509,229**

(22) Filed: **Nov. 14, 2014**

(57) CLAIM

The ornamental design for a switching device for producing, distributing or transforming electricity, as shown and described.

DESCRIPTION

FIG. 1 is a front elevation view of a switching device for producing distributing and/or transforming electricity showing our new design;

FIG. 2 is a rear elevation view thereof;

FIG. 3 is a top elevation view thereof;

FIG. 4 is a bottom elevation view thereof;

FIG. 5 is a left side elevation view thereof;

FIG. 6 is a right side elevation view thereof; and,

FIG. 7 is a front left side perspective view thereof.

The broken line portion of the figure drawings is included to show portions of the article hat form no part of the claimed design.

1 Claim, 7 Drawing Sheets
